UNITED STATES PATENT OFFICE.

JOHN W. CULMER, OF CLEVELAND, OHIO, ASSIGNOR TO THE NATIONAL COMPUTING SCALE COMPANY, OF SAME PLACE.

DESIGN FOR A STANDARD FOR SCALE-FRAMES.

SPECIFICATION forming part of Design No. 32,393, dated March 27, 1900.

Application filed February 26, 1900. Serial No. 6,641. Term of patent 14 years.

To all whom it may concern:

Be it known that I, JOHN W. CULMER, a citizen of the United States, residing at Cleveland, in the county of Cuyahoga and State of Ohio, have invented and produced a new and original Design for a Standard for Scale-Frames, of which the following is a specification, reference being had to the accompanying drawings, forming part thereof.

10 In the drawings, Figure 1 is a front elevation of a standard constructed in accordance with my design. Fig. 2 is an outside elevation thereof, and Fig. 3 is a horizontal section on line 3 3 of Figs. 1 and 2.

15 The leading or material features of my design, as shown in the drawings and most clearly in Fig. 1, consist of a short vertical base A, a longer vertical upper end C, which lies in a plane outside of the base, and a 20 curved middle part B, which connects said end sections, and is concavo-convex with respect to a vertical line, the concave side being the outer side.

25 In horizontal section the standard is in the form substantially of half of a hollow octagon, having symmetrically-arranged but unequal sides, the open side of this half-octagon being on the inner side of the standard. The front and rear sides D D' of the standard are widest 30 at their lower ends, and they gradually de-

crease in width toward their upper ends and are curved outward into a horizontal position, as is also the entire upper end of the standard, whereby to make a short cap-piece G. The outer side E of the standard (see Fig. 2) 35 is narrowest at the lower end and gradually increases in width to the upper end. The two corner-sections f f are of substantially the same width from bottom to top. On the lower end of the standard is an inwardly-extended 40 horizontal foot H.

In the outer side E of the standard are a plurality of holes—viz., an arch-shaped hole a in the base, two oblong holes b b in the curved middle part, a deep notch c in the upper end of the standard, and another hole c' 45 below this notch, but in the vertical upper part of the standard.

Having described my invention, what I claim as new, and desire to secure by Letters 50 Patent, is—

The design for a standard for scale-frames, substantially as herein shown and described.

In testimony whereof I hereunto affix my signature in the presence of two witnesses. 55

JOHN W. CULMER.
